UNITED STATES PATENT OFFICE.

JOSEPH R. BITTNER, OF PHILADELPHIA, PENNSYLVANIA, ASSIGNOR TO GRIFFITH TOOL WORKS, A FIRM, OF PHILADELPHIA, PENNSYLVANIA, COMPOSED OF PAUL A. GRIFFITH, WILLIAM K. WILSON, EDWARD J. GRIFFITH, AND CHARLES F. GRIFFITH.

SPREADER STRUCTURE.

Application filed November 21, 1922. Serial No. 602,337.

To all whom it may concern:

Be it known that I, JOSEPH R. BITTNER, a citizen of the United States, residing in the city and county of Philadelphia, State of Pennsylvania, have invented certain new and useful Improvements in Spreader Structures, of which the following is a specification.

This application constitutes, in part, a continuation of my application, Serial No. 531,698, filed January 25, 1922, and the invention relates to structures for spreading or expanding a member of wood or other suitable or similar material in a socket, to effect a firm or rigid connection between the said member and the socket.

One of the objects of my invention is to provide an improved form of fastening device for securing together members such as tool handles and tools and to provide means whereby the expanding devices may be reset from time to time as occasion may require.

More specifically, my invention consists in providing a wedge that may be driven into the end of a tool handle, to expand the same within the socket of a tool, and a combined locking and spreading member that may be driven against the head of the wedge to force the wedge farther into the handle, and which serves as a locking member to retain the wedge in place and also acts as an expanding or spreading member for the wooden handle.

Heretofore, locking members have been provided for holding wedges in position within the end of a tool handle, but such members are merely staples, the prongs of which spread apart when driven home. Difficulty has been experienced in driving the staples into position owing to the toughness of the wood—such as hickory—which is commonly employed for making tool handles. In order to overcome this objection, grooves or recesses have been provided in wedges to permit the partial insertion of the staple or locking member, after which the staple is driven the short remaining distance. Such holding means have been insecure and also resulted in a rough or irregularly shaped handle end. Furthermore, the wedges and locking staples have been disposed in planes at right angles to one another, so that, with a relatively thin handle, there was not sufficient material be-

tween the transversely disposed wedge or staple—as the case might be—and the side walls of the socket. Such side walls also seriously limit the width of the wedges or the locking and spreading movement of the staples.

The locking staples of the prior art serve merely as locking staples and perform no spreading function. Also, they present such small engaging surfaces to the top of the wedges that they could not be utilized to drive the wedge farther into the handle.

The wedge and combined locking and spreading devices of my invention are preferably disposed in parallel planes; the locking device completely overlies the wedge, when driven home, and presents a wide engaging surface to the top of the wedge to permit such resetting of the wedge as may be required through shrinking of the handle or otherwise.

For an illustration of some of the forms which my invention may take, reference is had to the accompanying drawing wherein:

Fig. 1 is a view, in end elevation, of a hammer and its handle equipped with my device.

Fig. 2 is a view thereof partially in section and partially in side elevation.

Fig. 3 is a side elevational view of my wedge and locking member in partially set position.

Fig. 4 is an edge view of the locking member.

Fig. 5 is an edge view of the wedge.

Figs. 6, 7, 8 and 9 are views similar to those of Figs. 2, 3, 4 and 5, but showing a modified form of device.

As shown in Figs. 1 and 2, the device is inserted into a handle 10 to expand the same within the socket or eye of a hammer 11, and comprises a wedge 12 and a locking member 13. The wedge may be of the usual form at its forward end, for convenience of insertion and effective spreading action, but toward its head, has its edges 14, 15, inclined as shown in Figs. 2 and 3, to provide partial guiding surfaces for the bifurcations 16 of the locking member 13. The head of the wedge 12 is flat and serves as a seat for the seating surface 17 of the locking member 13.

The oppositely disposed surfaces of the bifurcations 16 are beveled as shown in Figs.

2 and 3 so that such bifurcations will be spread farther apart when the member 13 is driven home, to render the member 13 effective both as a locking device for retaining wedge 12 in place and as a spreading member for farther expanding the handle 10. The bifurcations 16 are pointed as shown in Fig. 4 but are otherwise of general wedge form and are of such thickness that they will not bend or collapse when being driven into the handle. The engaging surface 17 is also of such dimension that the head of the member 13 will not be distorted or broken when it is driven against the head of the wedge 12 to force the wedge farther into the handle.

The structure shown in Figs. 6 to 9 is quite similar to the form above described, the only difference residing in the provision 20 of a rounded head upon the wedge 12^a which is engaged by the rounded surface 17^a of the locking member 13^a.

I have thus provided a fastening device that may be so disposed in a relatively thin 25 handle that the device is surrounded by ample material and is not seriously restricted as to size or range of spread; that presents a substantially smooth exterior having the appearance of only a single member for holding the handle; and that has a locking member which spreads readily and which has sufficient strength to resist hammer 30 blows when inserting the same and which serves also as an expanding member that 35 may also be utilized to drive the wedge farther into the handle from time to time as

may be necessary, to more tightly secure the handle in its tool.

What I claim is:

1. A locking device comprising a wedge member, a separate locking element overlying the head of said wedge member and provided with flared portions disposed over the edges of said wedge member, and with an engaging surface that abuts against the head 45 of the member, whereby the wedge member may be driven through the instrumentality of blows upon the said locking element.

2. A fastening device for tool handles and the like comprising a wedge having a flattened head, and a locking member overlying the wedge and provided with flared portions disposed at opposite edges of said wedge, the said locking member being also provided with a substantially flat engaging surface 55 disposed between its flared portions, in position to engage the said flattened head of the wedge, whereby the wedge is forced into a handle when the locking member is being driven into said handle.

3. A fastening device for tool handles and the like, comprising a wedge member, and a locking element overlying the head of said member, the said member and element being so disposed that the side faces 60 of said wedge member are substantially continuations of the side faces of said locking element.

In testimony whereof, I have hereunto affixed my signature this 17th day of November, 1922.

JOSEPH R. BITTNER.
